PISTON FOR INTERNAL-COMBUSTION ENGINES

Alan Hawker Chamberlain, Port Melbourne,
Victoria, Australia

Application November 4, 1950; Serial No. 194,170

Claims priority, application Australia
November 9, 1949

7 Claims. (Cl. 309—12)

1

This invention relates to pistons for internal combustion engines, and refers more particularly though not exclusively to pistons of trunk type having split skirts.

It is the customary practice in the reconditioning of internal combustion engines of automobiles to re bore the cylinders and fit new pistons upon wear setting up after considerable mileage. However, re boring of the cylinders being dependent upon the skill of the operator, is not always effective, and the prevailing labour costs are such as to necessitate a relatively heavy outlay to the motorist.

Now the principal objective of the present invention, aims at the elimination of the above disadvantage by the provision of an improved piston having the characteristic of variable diameters within predetermined limits to accurately fit a cylinder bore, either new or worn, and particularly a worn bore to take up slack to achieve in effect the reconditioning of the internal combustion engines to defer the necessity of re boring.

With the above stated principal objective in view, there is provided according to the invention, an adjustable piston of the type herein specified, comprising flexible skirt portions separated by a longitudinally disposed slot and at least one deformable member bridging the slot and embedded at each end in one of the flexible skirt portions said member including a portion thereof offset inwardly from alignment with the skirt portions, whereby a decrease or an increase of the extent of offset will respectively expand or contract the flexible skirt portions to fit a cylinder bore.

More specifically there is provided between the flexible skirt portions and extending transversely across the gap or split therebetween, a deformable member, parts of which on opposite sides of the gap or split are embedded in the flexible skirt portions, and which upon appropriate deformation spreads the skirt portions more widely apart or contracts the skirt portions more closely together.

The piston upon the skirt portions being thus appropriately adjusted, assumes a diameter to fit the bore of the cylinder. Thus in lieu of re boring the cylinders, the existing pistons may be conveniently expanded to fit the cylinders with a very substantial reduction in cost, time and labour.

The piston according to the invention can be used in engines which have been originally machined with bores of varying sizes, or engines

2

which have been reconditioned by a previous re boring.

It is the recognized practice to re bore cylinders to certain accepted nominal oversizes. However, cylinders so reconditioned are seldom held to close limits, it being the practice to finish the cylinder to an approximate oversize and then machine the piston to fit the cylinder. The piston according to the invention being adjustable over a reasonably wide range of sizes can be sold or distributed finished to the nominal standard oversize and then adjusted by the mechanic installing the piston so as to fit the particular bore.

Conveniently, in one practical arrangement the deformable member comprises a length of wire or metal strip which is disposed within the skirt of the piston and arranged to bridge or extend transversely across the longitudinal split in the piston separating the skirt portions.

The length of wire or metal strip for parts of the length thereof is embedded in the opposite skirt portions in the process of casting the piston. Alternatively, the length of wire or strip may comprise a complete ring or a substantially complete ring which is entirely embedded in the piston skirt, except at the part which bridges the gap between the skirt portions.

If a pair of strips or wires are used at a spaced distance apart to bridge the longitudinal slot, the strips or wires may comprise opposite sides of an open rectangular frame, the other opposite sides of which are embedded in the skirt portions in the casting process.

At the point at which the wire or strip bridges the longitudinal slot and extends between the skirt portions, the former is constructed with a kink or bend which is disposed substantially in parallel relation with the circumference of the piston.

The longitudinal slot or gap at the point at which the kink or bend is located is slotted or widened to provide access of a suitable tool to the kink or bend.

By striking or pressing upon the convex side at the apex or crown of the bend or kink, the bend or kink may be more or less straightened to thereby separate or expand the flexible skirt portions on opposite sides of the longitudinal slot, while upon application of pressure to the concave side at the apex, the bending or curvature of the strip or wire may be increased to contract or draw the skirt portions more closely together.

It will be apparent that the straightening of the bend or kink and resultant forcible expansion of the skirt portions will increase the major di-

ameter of the piston to fit a worn cylinder, while the increase in curvature of the bend or kink and resultant contraction of the skirt portions will decrease the diameter of an oversize piston to fit a cylinder of somewhat less diameter.

The metal comprising the wire or strip is non-resilient or inelastic and upon deformation the relative straightening or increased curvature of the kink or bend is retained, thereby maintaining the relative expansion or contraction of the skirt portions. Mild steel has been found suitable for the construction of the kinked wire or strip.

The invention will be better understood from the description of the illustrative adjustable trunk piston depicted in the accompanying drawings.

In these drawings:

Fig. 1 is a side elevation of the illustrative piston.

Fig. 2 is a side elevation partly sectional of the piston shown by Fig. 1.

Figs. 3 and 4 are part transverse sections on the lines 3—3 and 4—4 respectively of Fig. 1.

Fig. 5 is a longitudinal section on the line 5—5 of Fig. 1.

Fig. 6 is a view in perspective of a part of the illustrative piston shown separately.

Fig. 7 is a view in perspective of a part alternative to the part shown by Fig. 6.

Figs. 8 and 9 are diagrammatical views illustrating the actions of the tool shown by Fig. 8 in expanding and contracting the illustrative piston respectively.

Fig. 10 is a transverse section of a modified adjustable piston.

Referring to these drawings in more detail, the numeral 5 designates generally the illustrative piston having skirt portions 6 and 7 positioned on opposite sides of a longitudinally disposed slot 8 and located between the open or lower end of the piston and a partly circumferential slot 9 in which the slot 8 terminates at the upper end.

The skirt portions 6 and 7 are relatively thin and flexible, and it will be apparent that responsive to forces applied in directions substantially at right angles to the longitudinally disposed slot 8, the skirt portions 6 and 7 may be expanded by thrusting forces and contracted by reactive forces.

In order that the skirt portions may be readily expanded or contracted, there are provided strips 10 of a suitable mild steel bridging the slot 8 and mounted in the skirt portions 6 and 7, see particularly Figs. 3 and 4.

The strips 10 are located at required distances from the open end of the piston and from the partly circumferential slot 9, and the ends of the strips are embedded or incorporated in the skirt portions 6 and 7 during the process of casting the piston.

The part of each strip 10 bridging the longitudinally disposed slot 8 is formed with a bent, cranked, offset or curved section 11 which is centralised relatively to the longitudinal slot, while the portions 12 of the strips on opposite sides of the curved section 11 are approximately straight.

The metallic strips 10 may be separate and constructed as shown by Fig. 7, but in order to effect a secure bonding of the strips with the skirt sections 6 and 7, the former may comprise opposite sides of a rectangular frame 13, the other opposite sides 14 of which connect together the opposite strips 10 and are incorporated in the skirt portions 6 and 7 in the process of casting.

Referring more particularly to Figs. 3 and 4, it will be apparent that if the curved section 11 be straightened, the strip 10 will be lengthened and resultantly the skirt portions 6 and 7 will be thrust apart or expanded.

Conversely, if the bending of the curved section 11 be increased, the strip 10 will be shortened, and resultantly the skirt portions 6 and 7 will be drawn closer together or retracted.

Accordingly, it will be apparent that the piston 5 may be adjusted to accurately fit an engine cylinder by varying the curvature of the bent section 11 so as to expand or contract the skirt portions 6 and 7 as required.

In order to ensure flexibility of the skirt portions 6 and 7, stiffening ribs 28 are formed in the interior of the piston 5 at or about the ends of the skirt portions remote from the slot 8, and at these ends the skirt portions are somewhat reduced in thickness.

In the modified construction shown by Fig. 10, the bent section 11 bridging the slot 8 separating the skirt portions 6 and 7, comprises a part of a continuous wire ring 29 which is embedded in the piston in the process of casting, and moreover reinforces the latter.

The deformation of the bent section 11 in this modified construction to expand or contract the skirt portions 6 and 7 is effected precisely as hereinbefore described.

In order to enable the skirt portions 6 and 7 of this modified construction to be expanded and contracted the ribs 30 extending around the inner periphery of the piston and encasing the wire ring 29 may be recessed as at 31.

In accordance with recent or modern practice, the pistons 5 above described, are made of slightly elliptic form or shape, the plane of the minor axis passing through the centre of the 40 gudgeon or wrist pin bosses, and the plane of the major axis being perpendicular to the plane of the minor axis and coincident with the plane of oscillation of the connecting rod. The difference in length between the major and minor axes is of the order of .005 to .008 inch.

Referring again to Fig. 8, the skirt portions 6 and 7 in expanding will move radially outwards about the zones or areas of flexure lying approximately between the lines A defining the boundaries of these zones or areas, the expanding movements of the skirt portions being in the directions indicated by the feathered arrows.

Accordingly, it will be appreciated that the expansive movements of the skirt portions 6 and 7 will increase the ellipticity of the piston in the direction of the major axis, so that by such an adjustment the piston may be increased in size to compensate for wear.

Similarly, the skirt portions in contracting will move radially inwards about the zones or areas of flexure lying between the lines A as indicated by the feathered arrows in Fig. 9, thus reducing the ellipticity of the piston.

In order to enable a working tool to engage both sides of the number 11 with a view either to increasing the extent of the offset to reduce the peripheral dimensions of the skirt or to decrease the offset with a view to increasing the peripheral dimensions of the skirt, the slot is enlarged as at 32 where windows in the skirt portions are clearly illustrated. Any suitable working tool may therefore engage both sides of the member 11 to exert the required deforming action.

I claim:

75 1. In an adjustable piston having a head por-

tion, wrist pin bosses and a skirt depending from said head portion and separated into flexible skirt portions by a longitudinally disposed slot, said skirt defining thrust faces for the piston disposed at 90° rotation relatively to the wrist pin bosses, the provision of first integral stiffening means for each skirt portion extending longitudinally thereof adjacent each boss, second integral stiffening means for the skirt portions extending longitudinally thereof adjacent each side of the slot, a relieved portion for each skirt portion intermediate each first and second stiffening means defining a longitudinal axis of flexure, at least one deformable member bridging the slot and embedded at each end in the second stiffening means, said member including a portion thereof offset from alignment with the skirt portions, whereby an increase or decrease of the extent of offset will respectively decrease or increase the dimension across the thrust faces of the skirt by causing rotation of the flexible portions thereof about said axis portions without substantially disturbing the alignment of the wrist pin bosses, and the slot being enlarged at the location of said member to leave a substantial clearance for the engagement of a working tool with said member from either side to vary the extent of the offset thereof in either direction whereby the flexible skirt portions may be expanded or contracted to fit a cylinder bore.

2. An adjustable piston as claimed in claim 1, having a pair of said deformable members bridging the longitudinally disposed slot in spaced parallel relation.

3. An adjustable piston as claimed in claim 2, wherein the deformable bridging members are of flat bar section.

4. An adjustable piston as claimed in claim 2,

wherein the spaced deformable bridging members comprise parts of an open frame having other parts thereof embedded in the flexible skirt portions on opposite sides of the longitudinally disposed slot.

5. An adjustable piston as claimed in claim 4, wherein the open frame is of rectangular form having a pair of the opposite sides comprising the spaced deformable bridging members, and the other pair of opposite sides embedded respectively in each of the flexible skirt portions.

10 6. An adjustable piston as claimed in claim 1, wherein the deformable bridging member comprises a section of an annular member having the remainder thereof embedded within and extended around the piston wall and coaxial with the circumference of the piston.

15 7. An adjustable piston as claimed in claim 6, wherein the annular member comprises a ring of wire having therein a bend or kink comprising the deformable bridging member.
